UNITED STATES PATENT OFFICE.

AUGUST JOHNSON, OF BUTTE, MONTANA.

MINING COLUMN-BAR.

SPECIFICATION forming part of Letters Patent No. 726,066, dated April 21, 1903.

Application filed October 22, 1902, Serial No. 128,240. (No model.)

To all whom it may concern:

Be it known that I, AUGUST JOHNSON, a citizen of the United States, residing at Butte, in the county of Silverbow and State of Montana, have invented certain new and useful Improvements in Mining Column-Bars, of which the following is a specification.

My invention relates to improvements in mining column-bars—that is to say, a column 10 bar or support used when mining with a drill to facilitate the use of a drill in mining.

The object of my invention is the provision of a column-bar which can be quickly adjusted for use and which will be strong 15 and durable, simple and inexpensive of construction, and thoroughly efficient and practical for the intended purpose.

With this object in view my invention consists of an adjustable column-bar embodying 20 novel features of construction and combination of parts substantially as disclosed herein.

Figure 1 represents a side elevation of a column-bar for mining constructed in accordance with and embodying my invention. 25 Fig. 2 represents a side elevation, partly in sections, to show interior details. Fig. 3 represents a detail view of parts of my column-bar detached.

In the drawings, the letter A indicates the 30 base or foundation of my column-bar, which is a casting having the vertical tubular stem B, the enlarged chamber C, having the opening D on one side covered by a curved metal dust-cap E, and on the other side the casting 35 is formed with the horizontal bearing F, and on the inner side of its base portion is formed with a vertical disposed bearing G, and the outer face of the base portion is formed with the ribs H, the purpose of which is to engage 40 the surface and hold the base portion from turning. In the vertical bearing is mounted the lower end of the screw J, which is keyed at said lower end, by means of the key K, to the beveled gear-wheel L, which beveled gear-wheel meshes with the vertical driving beveled pinion M, mounted on the short horizontal shaft N, said shaft carrying at its outer 45 end the disk O, provided with a series of openings P to receive the end of the hand-lever Q, the purpose of which is to revolve 50

the driving-pinion which revolves the beveled gear, which, being connected to the screw, rotates the screw and adjusts the nut R, which is connected by means of the lug S, fitting in opening T of the column-bar U, and thus adjusts the column-bar up and down or vertically to suit the place where it is to be used. The column-bar is of the desired 55 length and is preferably a hollow tube, and in the upper end of said column-bar is secured the cap V, provided with the ribs W, which serve in connection with the ribs on the base of the casting to secure the column-bar firmly in position by said ribs cutting into the surface where the operation of mining is being performed. From this construction it will be seen that my bar can be placed 60 in position for use and adjusted instantly to suit the size or space in which it is to be employed and that it will form an absolutely 65 perfect support for the wall and enable the drill to be used with ease. It will also be noticed that my column-bar is composed of few 70 parts, rendering the construction extremely simple and inexpensive, very strong and durable, and entirely efficient in every respect. 75 It will also be understood that the working parts of my column-bar are protected from dirt or dust and can be easily oiled, when desired, by removing the dust-caps, which is a 80 feature of paramount importance in such a device.

I claim—

1. In a mining column-bar, the combination of the hollow base or support having the 85 opening on one side and the bearing on the other side, the protecting-cover for the opening, the shaft mounted in the bearing, the bevel-pinion on the inner end of the shaft, the disk on the outer end of the shaft having 90 openings to receive a lever for turning said disk, the vertical screw mounted in the hollow base, the bevel-gear therein meshing with the bevel-pinion, and the column-bar connected with said screw and adjusted 95 thereby.

2. In a miner's column-bar, the combination of a hollow base having securing exterior ribs, a horizontal shaft mounted in the base, means on the outer end of the shaft for 100

turning the said shaft, a vertical disposed bevel-pinion on the inner end of the shaft, a horizontal bevel-gear meshing with said pinion, a vertical screw mounted in the base and connected to said gear-wheel, a collar having lugs and a column resting on the collar and having recesses to receive the lugs, the screw engaging the collar and column,

and a cap on the column having exterior securing-ribs.

In testimony whereof I affix my signature in presence of two witnesses.

AUGUST JOHNSON.
